UNITED STATES PATENT OFFICE

HORACE C. HINKLEY, OF KEOKUK, IOWA, ASSIGNOR TO IOWA CAN COMPANY, OF
KEOKUK, IOWA, A CORPORATION OF IOWA

INSULATING PACKAGE

Application filed December 17, 1930. Serial No. 503,045.

This invention relates to insulating containers, and aims generally to provide a container of improved construction made almost entirely out of corrugated fibre board, which may be used to hold a can of ice cream or the like and which may also hold a piece of dry ice to preserve the ice cream.

In the accompanying drawings forming a part of this specification,—

10 Fig. 1 is a longitudinal sectional view through the improved container, showing a can inside in elevation;

15 Fig. 2 is a cross sectional view through the container and can;

20 Fig. 3 is a detail section showing how the joint in the insulating liner is made when single face corrugated board is used; and

Fig. 4 is a view similar to Fig. 3, but showing how the joint is made when double face corrugated board is used.

Referring particularly to the drawings, there is shown an insulating container comprising a generally cylindrical body 5, preferably of paper board, closed by flanged lids 6 and 7 at its opposite ends. Within the body is a corrugated board liner of at least two thicknesses of material, if the corrugated board is single face, or of at least one thickness, if the corrugated board is double face.

25 This liner is so placed within the cylindrical body 5 that the air spaces between the individual corrugations extend longitudinally of the body, as shown. When single face board 8 is used (Fig. 3), the two thicknesses are so 30 cut as to fit, one inside the other, within the body 5, with the joint 9 of the inner single face board staggered or displaced angularly relative to the joint 10 of the outer thickness of board. The two layers of single face board

35 may be united by a little glue or with one or more staples (not shown) to prevent the joints 9, 10 from becoming alined, which would leave a narrow air gap at one point in the periphery of the liner, thus diminishing its efficiency as an insulating wall. In the case of double face board 8^a (Fig. 4) no shifting of the layers is possible, unless more than one thickness of double face board is used. In this event, relative movement may be ob-

of the inner layer with the inner face of the outer layer, as will be understood without illustration. In any case, when the liner is in position, the joint is substantially closed to air currents, so that the article within the container is well insulated.

Between the ends of the liner and the ends of the outer container, insulating media in the form of heavy disks 11, 12 are placed. These are preferably of double face corrugated board, as shown. Within the closed compartment formed by the liner and the disks 11, 12, the ice cream can 13 or other article is placed. Preferably the inside diameter of the liner but slightly exceeds the outside diameter of the can, so that a very narrow space is left between them. However, between the top of can 13 and the top disk 11, a fairly large space may be left, as shown in Fig. 1, and in this space a piece of dry ice or solidified carbon dioxide (not shown) may be placed. The vapors from this material will slowly move downwardly past the sides of the can and will gradually displace the warm air initially in the container, the warm air being slowly expelled, because of the slightly higher pressure within the container, out through the ends underneath the flanges of the caps.

80 The described container is of the simplest and most inexpensive construction, and yet it is most satisfactory as a container to hold ice cream cans for considerable periods of time without deterioration of the container or of the ice cream.

85 Obviously, the invention has other uses and applications and may be embodied in several forms neither shown nor described.

What I claim is:—

1. An insulating package comprising, in combination, a container consisting of a cylindrical paper body and two flanged caps closing the opposite ends of the body; a liner of a plurality of layers of corrugated board inside the container, said liner being truly annular in cross-section and having a lapped joint extending longitudinally; said lapped joint being formed by staggering the joints in the several layers of flexible corrugated board; and insulating spacers of a plurality

of layers of corrugated board located between the ends of the aforesaid liner and the flanged caps.

2. An insulating package comprising, in combination, a container consisting of a cylindrical paper body and two flanged caps closing the opposite ends of the body; a liner of a plurality of layers of single face corrugated board inside the container, said liner being truly annular in cross-section and having a lapped joint extending longitudinally; said lapped joint being formed by staggering the joints in the several layers of flexible corrugated board; and insulating spacers of a plurality of layers of corrugated board located within each of the flanged caps.

3. An insulating package comprising, in combination, a container consisting of a cylindrical paper body; a liner of corrugated board inside the container, said liner being truly annular in cross-section and having a lapped joint extending longitudinally; said lapped joint being so constructed and arranged that the liner has exactly the same thickness at the joint as elsewhere, the overlapping parts being disunited but preventing the movement of convection currents at the joint; and insulating means between the ends of the liner and the ends of the paper body.

30. In testimony that I claim the foregoing as my own, I have hereto affixed my signature.

H. C. HINKLEY.
